NECKTIE

Maurice Black, Detroit, Mich.

Application November 25, 1933, Serial No. 699,785

13 Claims.

(Cl. 2—146)

This invention relates to improvements in neckties, and has particular reference to reversible or double faced ties which are intended to be worn with either face and either extremity thereof exposed to view.

It is an object of the invention to provide a necktie consisting of two separate facings of similar size and shape sewn together along their longitudinal margins so that the stitching is concealed, and having relatively narrow and thin, yet strong and flexible reinforcing strips held between the sewn facing margins to strengthen the sides of the tie and hold it in shape, and also to prevent the stitches from ripping.

Another object of the invention is to provide such a necktie with a resilient, flexible lining; and, since my construction necessitates the sewing of the facing margins and strips and subsequently turning the tie inside out so as to conceal the stitches from both facings, it is necessary that the longitudinal lining margins shall not extend quite to the tie margins as otherwise the sides of the tie would appear thick and clumsy. I therefore attach the lining to the reinforcing strips adjacent their inner margins and thereby hold the lining in place between the facings.

A further object of the invention is to provide such a necktie wherein end lining portions having marginally secured reinforcing strips extend from both extremities to a central lining portion which normally passes around the wearer's neck, the central lining portion being thin, yet strong and having the inner extremities of the reinforcing strips also connected to it. Thus I aim to provide ample reinforcement for the facings throughout their entire length, and at the same time reduce the thickness of the medial portion of the necktie so that it may more readily slip beneath a collar.

Yet another object of the invention is to provide a simple and convenient method of manufacturing such a necktie.

Having thus briefly and broadly outlined some of the major objects and advantages of the invention I will now proceed to describe an embodiment thereof, and a preferred method of manufacture, with the aid of the accompanying drawing, in which:

Figure 1 illustrates a partial plan view showing one end lining portion, the reinforcing strips secured thereto, and a part of the central lining member to which both the former are secured.

Figure 2 is a partial plan view showing parts of two facings, two reinforcing strips and one end

lining, and also a portion of the central lining member.

Figure 3 shows a plan view of a finished necktie, both sides of which appear identical.

Figures 4 and 5 are sections on the line 4—4 and 5—5 respectively of Figure 2.

Figures 6 and 7 are sections on the lines 6—6 and 7—7 respectively of Figure 3.

Figure 8 is a detail showing a preferred method of finishing the ends of the facings.

In the manufacture of my neckties I employ two facings 1 and 2, two end lining portions 3, a central lining member 4, and a plurality of reinforcing strips 5.

The facings 1 and 2, which are generally cut on the bias, are identical in size and shape, and the extremities of both facings are balanced, by which I mean they are of identical width and contour so that when the facings are folded back upon one another centrally of their length their longitudinal margins coincide throughout their length. For the type of neckties shown in the drawing the central portions 1a and 2a of the facings are of uniform width while their extremities are tapered so that their width increases uniformly towards their ends.

The lining consists of a central lining member 4 of uniform width throughout its length and also of substantially the same length and width as the central facing portions 1a and 2a. Secured to each extremity of the central lining member 4 is an end lining portion 3 which is materially narrower than those portions of the facings 1 and 2 between which they are to be arranged. The central lining member is made of thin yet strong material which is cut with either its warp or woof threads running longitudinally of the tie. The end lining portions 3 are made of heavier resilient material, preferably wool, and are usually cut on the bias, that is with the warp threads running diagonally.

The reinforcing strips 5 are made of thin, strong material and are also cut on the bias. The width of these strips is such that when their outer edges coincide with opposed longitudinal facing margins, the adjacent edges of each pair of strips project inwardly sufficiently beyond the end lining portions 3, which are centrally located on the facings 1 and 2, to permit attachment of the strips to the said lining portions. The strips 5 extend from the ends of the facings 1 and 2 to the central lining member 4 to which they are secured.

The preferred method of manufacture is as follows: Two identical facings 1 and 2 are laid one

upon the other with their outer faces contiguous; two reinforcing strips 5 are sewn as shown at 6 longitudinally along their inner margins to the opposite sides of each of two end lining portions 3, and then each of the latter and its strips 5 are sewn transversely across their inner ends to one extremity of the central lining member 4, as indicated at 7. The completed lining structure is then laid upon one of the facings 1 or 2 with the outer 10 margins of the strips 5 and of the central lining member 4 substantially coinciding with the longitudinal margins of the facings 1 and 2. The four reinforcing strips 5 and the central lining member 4 are then sewn to the facings 1 and 2 by stitching 8. The outer extremities of the strips 5 and of the end lining portions 3 are then bevelled as shown at 5a and 3a respectively to conform to the bevel of the V-shaped ends of the facings 1 and 2. The facing ends are, for the 15 present, left unstitched to permit the tie to be turned inside out. This is now done so that the outer faces of the facings are exposed. The tie is then pressed after which both ends of the tie are again turned wrong side out for a short distance as shown in Figure 8, and the ends of the 20 facings 1 and 2 are then sewn together by stitching 9 with their reverse faces outward. It will be noted that on one side of the bevelled end of each extremity this stitching is left incomplete 25 where a portion of the correctly turned part of the tie passes between the ends of the facings which are wrong side out. This gap has to be left to permit the end of the tie to be pulled through so that then the entire length of the tie 30 is right side out. This unstitched portion may be subsequently sewn up by hand.

Due to the resilience of the lining portions 3, and to the fact that this lining material as well as the strips 5 and facings 1 and 2 are cut on the bias, the tie will withstand considerable hard usage without losing its shape. In order that additional elasticity may be afforded to further prevent distortion of the tie I prefer that the stitching of the strips 5 both to the facings 1 and 2 and to the lining portions 3 be done with chain stitch. It will also be noted that while there are two folded layers of facings and one folded reinforcing strip along each margin of the tie for the greater portion of its length, the tie 45 does not present a bulky or clumsy appearance due to the relative thinness of these materials compared to the end lining portions 3 which terminate a short distance from the longitudinal margins. Further the central lining member 4 maintains a sufficient tie thickness centrally of its 50 length.

While in the foregoing the preferred embodiment of the invention has been described and shown, it is understood that the construction is susceptible to such alterations and modifications as fall within the scope of the appended claims.

What I claim is:

1. A necktie consisting of two similar facings secured to one another along their longitudinal margins, reinforcing strips secured to said facing margins and lying between the facings, and a lining between the facings having its opposed longitudinal margins secured to said strips.
2. A necktie consisting of two similar facings secured to one another along their longitudinal margins, narrow reinforcing strips also secured to the facing margins and lying between the facings, and a lining between the facings, the end portions of the lining being narrower than the facings and being secured to said strips by

which said end portions are held centrally between the longitudinal facing margins.

3. A necktie consisting of two similar facings joined to one another along their longitudinal edges so that the exposed faces appear identical, a reinforcing strip secured to each pair of longitudinal facing edges, and a lining between the facings having each of its edges secured to the inner margin of one of the strips. 5

4. A tie consisting of two similar facings having their longitudinal margins inturned, the inturned margins of each facing being secured to the adjacent inturned margins of the other facing, spaced and opposed reinforcing strips each having one longitudinal margin secured to one 15 pair of connected facing margins and being inwardly folded between the facings, and a flat unfolded lining portion narrower than said facings supported by each opposed pair of reinforcing strips. 20

5. A necktie consisting of two similar facings secured to one another along their longitudinal margins so that their outer faces appear identical, narrow reinforcing strips secured to the connected facing margins, said strips being arranged 25 in opposed pairs extending longitudinally from opposite ends of the tie, and a central lining member between the facings to which the adjacent ends of the strips are secured.

6. A necktie consisting of two similar facings secured to one another along their longitudinal margins, a relatively short lining member centrally of the length of the tie between said facings and of the same width as the portions of the facings between which it lies, and an end lining portion secured to each end of the lining member and extending between the facings, said lining portions being narrower than the portions of the facings between which they lie. 30

7. A necktie consisting of two similar facings secured to one another along their longitudinal margins, a relatively short lining member centrally of the length of the tie between said facings and of substantially the same width as those portions of the facings between which it lies, 45 said lining member being marginally held between the facings, and an end lining portion secured to each end of the lining member, said lining portions being narrower than the portions of the facings between which they lie, in combination with means holding said lining portions spaced from both longitudinal margins of the facings. 50

8. A tie consisting of two similar facings, narrow opposed reinforcing strips, and a lining consisting of two thick end portions narrower than the portions of the facings between which they lie and a thinner and wider central lining member connecting the end portions and being of substantially the same width as the portions of the facings between which it lies, said reinforcing strips extending along both longitudinal margins of the facings from both extremities, said facings being longitudinally sewn together and to the reinforcing strips and the central lining member, and the end lining portions being secured to opposed pairs of the reinforcing strips. 55

9. A method of making a necktie consisting of taking two facings of similar size and shape and placing them upon one another with their outer faces contiguous, securing the inner margins of two spaced and relatively narrow reinforcing strips along opposite longitudinal edges of a lining, placing the outer longitudinal edges of the 60

strips flush with the edges of the facings, securing the two facings and one strip together along both sides of the facings adjacent their longitudinal edges, and turning the tie inside out so that the strips and lining are hidden and the outer faces of the facings are exposed to view.

5. 10. A method of making a tie consisting of taking two facings of identical size and contour and placing them one upon the other with their edges coinciding, forming a lining consisting of a central lining member to the extremities of which narrower and thicker end lining portions are attached, securing reinforcing strips so that each projects laterally from one side of one end lining portion, laying the lining upon the facings so that the outer longitudinal margins of the strips coincide with the longitudinal margins of the facings, and sewing longitudinally along the facings and along both sides thereof so that the stitching passes also through the strips and the central lining portion, and turning the tie inside out so that the strips and hidden and the outer faces of the facings are exposed to view.

10. 15. 20.

11. A necktie consisting of two identical facings having their margins inturned and sewn together, end linings narrower than said facings and concealed between them, and means holding these lining portions in position transversely centrally of the tie.

12. A necktie consisting of two identical facings having their margins inturned and sewn together, end linings of a width not greater than the distance between the opposed inturned facing edges and concealed between said facings, and means holding these linings transversely of the tie.

13. A necktie consisting of two identical facings having their longitudinal margins folded inwardly and stitched together, a central lining member through the longitudinal margins of which the stitching also passes, and narrow opposed reinforcing strips extending longitudinally between the extremities of the facings also held by said stitching, the adjacent ends of the strips being also secured to the lining member.
